UNITED STATES PATENT OFFICE.

AUGUST GOERTZ, OF NEWARK, NEW JERSEY.

BELT-BUCKLE.

SPECIFICATION forming part of Letters Patent No. 403,263, dated May 14, 1889.

Application filed November 28, 1888. Serial No. 292,068. (No model.)

To all whom it may concern:

Be it known that I, AUGUST GOERTZ, of Newark, in the county of Essex and State of New Jersey, have invented certain new and 5 useful Improvements in Buckles for Belts, of which the following is a specification.

This invention relates to an improved buckle for ladies' and other belts, by which the free end of the belt can be clamped in an 10 effective manner without injuring the end of the belt and without requiring the perforating of the same for the tongue or other locking device of the buckle; and the invention consists of a buckle for belts, which is composed 15 of a main plate provided at both ends with guide-slots, a raised rib parallel with said guide-slots, and with bent-up ears which are made integral with the main plate and to which a cam-plate is pivoted that binds on 20 the end of the belt placed over the rib, so as to rigidly retain the same in position after it has been passed through the guide-slots and below the pivoted cam-plate of the buckle.

In the accompanying drawings, Figure 1 25 represents a front view of my improved buckle, shown as applied to a belt. Fig. 2 is a horizontal section of the same on line $\alpha\alpha$, Fig. 1; and Fig. 3 is a front view of the buckle with the free end of the belt removed there- 30 from.

Similar letters of reference indicate corresponding parts.

Referring to the drawings, A represents the main plate of my improved buckle, which is 35 made of square or other shape and attached, by means of prongs $a a$, that are punched out of the body of the plate, permanently to one end of the belt B. The prongs $a a$ pierce the belt and are clinched at the back of the same, 40 so as to firmly retain the main plate A at four or more points on the end of the belt B. The main plate A is provided at both ends with guide-slots C C, which are formed by guide-pieces C' C', that are made integral with the 45 main plate and bent forward so as to be parallel with the same at such a distance as to permit the convenient passage of the free end

of the belt through the guide-slots C C. The main plate A is further provided, near one guide-slot C, with a raised rib, D, which is 50 parallel with the guide-slots C, said rib serving, in connection with a cam-plate, E, to firmly clamp the free end of the belt after the same is passed through the guide-slots C C and below the cam-plate E, as shown in Fig. 2. 55 The cam-plate E is pivoted by a transverse pin, e, to ears e' , that are made integral with the main plate and bent up at right angles to the same near the rib D, the cam-plate swinging on said ears either toward or away from 60 the main plate A, so as to clamp or release the free end of the belt B, as required.

As my improved buckle consists of only three pieces, the main plate A, the cam-plate E, and the transverse pivot-pin e, it forms a 65 very simple and reliable device for connecting the ends of a belt, while it may be manufactured at comparatively low price, as the main plate, with its guide-pieces e' , rib D, ears e, and prongs a , is punched and stamped by 70 suitable dies. The free end of the belt is tightly clamped by the rib of the main plate and the pivoted cam-plate without being unduly stretched or injured and without requiring the perforating of the free end of the 75 belt for the buckle and tongue.

Having thus described my invention, I claim as new and desire to secure by Letters Patent—

A buckle for belts, composed of a main plate provided with guide-slots at both ends, 80 fastening-prongs made integral with said plate, a raised rib in said plate parallel with said slots, bent-up ears, also made integral with the plate, and a cam-plate pivoted to said ears close to said rib, substantially as set 85 forth.

In testimony that I claim the foregoing as my invention I have signed my name in presence of two subscribing witnesses.

AUGUST GOERTZ.
